Primary Examiner — Cynthia Underwood*(74) Attorney, Agent, or Firm* — Jon Gibbons; Fleit Gibbons Gutman Bongini & Bianco P.L.(57) **CLAIM**

The ornamental design for an electronic device shell, as shown and described.

DESCRIPTION

FIG. 1 is a first perspective view of the electronic device shell;
FIG. 2 is a second perspective view thereof;
FIG. 3 is a first elevational view thereof;
FIG. 4 is a second elevational view thereof;
FIG. 5 is a first side elevational view thereof;
FIG. 6 is a second side elevational view thereof;
FIG. 7 is a top plan view thereof;
FIG. 8 is a bottom plan view thereof;
FIG. 9 is a first perspective view of the electronic device shell in another configuration;
FIG. 10 is a second perspective view thereof;
FIG. 11 is a first elevational view thereof;
FIG. 12 is a second elevational view thereof;
FIG. 13 is a first side elevational view thereof;
FIG. 14 is a second side elevational view thereof;
FIG. 15 is a top plan view thereof; and,
FIG. 16 is a bottom plan view thereof.
